CLAIM

The ornamental design for a heat press, as shown and described.

DESCRIPTION

FIG. 1 is a front, right, top isometric view of the heat press in a closed configuration;

FIG. 2 is a rear, left, top isometric view of the heat press in the closed configuration;

FIG. 3 is a front elevation view of the heat press in the closed configuration;

FIG. 4 is a rear elevation view of the heat press in the closed configuration;

FIG. 5 is a left side elevation view of the heat press in the closed configuration;

FIG. 6 is a right side elevation view of the heat press in the closed configuration;

FIG. 7 is a top plan view of the heat press in the closed configuration;

FIG. 8 is a bottom plan view of the heat press in the closed configuration;

FIG. 9 is a front, right, top isometric view of the heat press in an open configuration;

FIG. 10 is a rear, left, top isometric view of the heat press in the open configuration;

FIG. 11 is a front elevation view of the heat press in the open configuration;

FIG. 12 is a rear elevation view of the heat press in the open configuration;

FIG. 13 is a left side elevation view of the heat press in the open configuration;

FIG. 14 is a right side elevation view of the heat press in the open configuration;

FIG. 15 is a top plan view of the heat press in the open configuration; and,

FIG. 16 is a bottom plan view of the heat press in the open configuration.

(Continued)

The shade lines in the figures show contour and not surface ornamentation. The broken lines in the figures form no part of the claimed design.
